UNITED STATES PATENT OFFICE.

JOHN E. WEEKS, OF THREE RIVERS, MICHIGAN.

STEAM-SUPERHEATER.

1,190,493.

Specification of Letters Patent. Patented July 11, 1916.

Application filed September 24, 1915. Serial No. 52,441.

To all whom it may concern:

Be it known that I, JOHN E. WEEKS, a citizen of the United States, residing at Three Rivers, in the county of St. Joseph, 5 and State of Michigan, have invented certain new and useful Improvements in Steam-Superheaters, of which the following is a specification, reference being had therein to the accompanying drawing.

This invention relates to certain new and useful improvements in steam superheaters, the object being to provide a superheater which can be readily placed in position within the smoke box of an ordinary boiler 15 and adjusted so that the fire tubes thereof will be in alinement with the fire tubes of the boiler.

Another object of my invention is to provide a superheater which is supported within 20 the smoke box by a series of positioning screws whereby the heater can be readily positioned within the smoke box or removed therefrom to make the necessary repairs.

Another object of my invention is to provide 25 a superheater which is so constructed that priming is prevented so as to eliminate the use of a priming valve.

Another object of my invention is to provide 30 a superheater in the form of a drum having an inlet pipe extending from the dome of the boiler of a greater size than the outlet extending to the engine so as to prevent the engine drawing steam from the superheater.

Another and further object of my invention 35 is to provide a superheater which is exceedingly cheap and simple in construction and one which is provided with a central partition having a series of openings adjacent its lower end so as to cause the steam entering the same to pass downwardly over a series of fire tubes and then upwardly over a series of fire tubes so as to heat the same before the same is conveyed to the engine.

Other and further objects and advantages 40 of the invention will be hereinafter set forth and the novel features thereof defined by the appended claims.

In the drawings: Figure 1 is a longitudinal 45 section through a boiler showing the superheater in position within the smoke box, Fig. 2 is a section taken on line 2—2 of Fig. 1, and Fig. 3 is a detail perspective view of the partition.

Like numerals of reference refer to like 50 parts in the several figures of the drawings.

In the drawings, 1 indicates an ordinary form of boiler having a series of fire tubes 2, and the usual dome 3, to which is connected a steam pipe 4 for conveying the steam to the superheater as will be herein-after fully described, said boiler having a smoke box 5, provided with the usual smoke stack.

My improved construction of superheater 55 comprises a drum 6, having a series of fire tubes 7, adapted to be placed in alinement with the fire tubes 2 of the boiler, so as to allow the heat units to pass through the fire tubes thereof, so as to thoroughly heat 70 the steam passing through the superheater. The superheater is provided with an inlet 7, to which is connected the steam pipe 4; by a suitable coupling member, and with an outlet 8, to which is connected a pipe 9, 75 adapted to extend to the engine. The pipes 4 and 9 extend through suitable apertured bosses formed in the shell of the smoke box, and the pipe 4 is of larger diameter than the pipe 9 so that the supply of steam to the 80 superheater will be greater than the exit of the steam therefrom. The drum 6, forming the superheater, is provided with a central partition 10, having a series of openings 11 adjacent its lower end, through 85 which the steam entering the compartment 12, passes into the compartment 13, so as to cause the steam to pass downwardly over the series of fire tubes in its passage through the compartment 12 and up over the series 90 of fire tubes in its passage through the compartment 13.

The shell of the smoke box is provided 95 with a plurality of bosses, provided with threaded bores 14, in which are mounted 95 positioning screws 15 which have their inner ends loosely mounted in sockets 16, formed in the shell of the superheater so that by adjusting the pins, the superheater can be adjusted in the smoke box so that the fire 100 tubes thereof will be in alinement with the fire tubes of the boiler, spacing pins also being employed for holding the superheater spaced from the tube sheet of the boiler, said pins being mounted within sockets 105 formed respectively within the tube sheet and superheater as clearly shown in Fig. 1.

It will be seen that by adjusting the positioning screws 15, the superheater can be so positioned within the smoke box so that 110 the flues thereof will be in alinement with the flues of the boiler, and that the same

will be firmly held in adjusted position and in such a manner that by loosening the positioning screws the superheater can be moved out of the way in the smoke box so 5 that any necessary repairs can be made to the boiler.

From the foregoing description it will be seen that I have provided a superheater for a boiler comprising a drum mounted within 10 a smoke box upon a series of positioning screws, and having a pair of compartments, one compartment being provided with an inlet adjacent its top, and the other with an outlet adjacent its top, said compartments 15 communicating with each other adjacent the bottom so as to cause the steam to travel around the fire tubes in its passage through the superheater, whereby the same will be thoroughly heated so as to prevent water 20 from being carried by the steam to the cylinder of the engine.

What is claimed is:—

1. The combination with a steam boiler for a smoke box, of bosses formed on said box provided with threaded bores, positioning screws working in said bores and a drum provided with sockets arranged within said smoke box adapted to receive the ends of said positioning screws.
2. The combination with a steam boiler having a smoke box, of a drum arranged within the smoke box provided with a plurality of sockets, a plurality of positioning screws carried by the boiler having 35 their ends arranged within said sockets for positioning said drum within said smoke box.
3. The combination with a steam boiler having fire tubes and a smoke box, of a drum provided with fire tubes arranged within said smoke box, said drum being provided with sockets, means for spacing said drum from the tube sheet of the boiler, and

positioning screws carried by the casing of the smoke box working within said sockets. 45

4. The combination with a steam boiler having fire tubes and a smoke box, of a superheating drum disposed within said smoke box having horizontally disposed fire tubes, said drum being provided with sockets, 50 means for spacing said drum from the tube sheet of the boiler, and a plurality of positioning screws extending through the wall of the smoke box having their ends mounted within said sockets for positioning said 55 superheater within said smoke box.

5. The combination with a steam boiler having horizontally disposed fire tubes and a smoke box at one end thereof, of a drum disposed in said smoke box provided with 60 horizontally disposed fire tubes, a series of independently adjustable supports for supporting said drum in said smoke box with the fire tubes thereof in alignment with the fire tubes of the boiler, said drum having 65 a vertically disposed partition arranged centrally therein between the fire tubes thereof, the ends of said partition being bent outwardly in opposite direction to provide flanges for securing said partition within 70 said drum to the top and bottom thereof, said partition being provided with a series of openings adjacent the bottom affording communication between the two compartments, formed by said partition, one of said 75 compartments being provided with an outlet extending from the upper end thereof and the other compartment being provided with an inlet of a larger diameter than the outlet. 80

In testimony whereof I affix my signature in presence of two witnesses.

JOHN E. WEEKS.
